JURJEN S. HIGH, OF WILKINSBURG, PENNSYLVANIA, ASSIGNOR TO WESTINGHOUSE ELECTRIC & MANUFACTURING COMPANY, A CORPORATION OF PENNSYLVANIA

REPRODUCING DEVICE

Application filed June 24, 1927. Serial No. 201,049.

My invention relates to reproducing devices and more particularly to "pick-up" devices designed and intended to translate the sinuosities of the usual phonograph records into electrical fluctuations that are subsequently amplified and utilized to actuate a loud-speaking telephone or its equivalent.

One object of my invention is to provide a pick-up device that shall be responsive to a wide range of sound-frequencies.

Another object of my invention is to provide a pick-up device that shall be free from moving circuit-connectors and, consequently, subject to only slight deterioration through use.

Another object of my invention is to provide a pick-up device that may be easily adjusted to preferentially respond to high or low frequencies.

Another object of my invention is to provide, in a pick-up device, adjustable damping means that shall also serve to center certain of the elements of the device with reference to other elements thereof.

Another object of my invention is to provide, in a pick-up device, a needle-holding lever of an improved type.

At the present time there is a very decided tendency toward the electrification of phonograph reproducing devices. In other words, instead of having the phonograph reproducer convert the sinuosities of the record directly into air vibrations, they are first translated into electric-potential, or current, fluctuations which, in turn, are utilized to control a thermionic amplifying system similar to those now well known in connection with radio receiving apparatus. A complete system of the type referred to is shown in the patent to Jones, No. 1,531,252, to which reference may advantageously be made in order to gain a clear understanding of the functions of a device constructed according to my invention.

The pick-up devices heretofore used have been of four general types, electromagnetic, microphonic, electrostatic, and electrodynamic. The electrodynamic type is exemplified in the Jones Patent, No. 1,531,222, the microphonic type in a patent to Moore, No.

1,583,067, the electrostatic type in a patent to Groenebaum, No. 1,544,001, and the electromagnetic in a patent to Egerton, 1,284,623.

My invention is concerned primarily with a modification of the electrodynamic type and is in the nature of a radical improvement on pick-up devices of that type, as known to the prior art.

According to my invention, I construct an electrodynamic pick-up in a manner analogous to the manner in which a step-up transformer is made, utilizing for the primary coil a single turn, or a plurality of turns which are short circuited, and so actuate the said primary coil in a magnetic field that eddy-currents are induced therein. The eddy-currents so produced inductively affect a secondary coil associated with the magnetic circuit which generates the field referred to, and the output of the secondary coil is utilized to control a thermionic amplifier, in the manner referred to previously.

Among the novel features of my invention, are those particularly set forth in the appended claims. The invention, in its generic aspect, however, as well as further objects and advantages thereof, will best be understood by reference to the following description of certain specific embodiments taken in connection with the accompanying drawings, in which:

Figure 1 is a view, partly in section and partly in elevation, of a preferred embodiment of my invention, taken along a line corresponding to the line I—I of Fig. 2.

Fig. 2 is a front view of the device, the cover plate being removed.

Fig. 3 is a view, partly in elevation and partly in section, of a preferred form of self-adjusting bearing, taken along a line corresponding to the line III—III of Fig. 4.

Fig. 4 is an end elevational view of the device shown in Fig. 3.

Fig. 5 is a view, partly in elevation and partly in section, of a modified form of self-adjusting bearing.

Fig. 6 is a sectional view, taken along a line corresponding to the line VI—VI of Fig. 5, as viewed from the left.

Referring specifically to Figs. 1 and 2, a

100

preferred embodiment of my invention comprises a circular base plate 1 of magnetic material which is shrunk onto one end of a permanent magnet 2. The base portion is provided with screw threads 3 by means of which a shell element 4 is affixed thereto. The shell element 4 is provided with an inwardly projecting circular rim 5, the inner edge of which approaches to within a short distance of the pole piece 2. The upper edge of the shell element 4 is provided with screw threads 6 by means of which a second rim 7 is affixed thereto. The inner edge of the rim 7 also approaches to within a short distance of the central pole piece, the space between the rims 5 and 7, and the pole piece 2, constitutes an air gap in the magnetic circuit.

The annular space between the elements 5 and 7 accommodates a secondary coil 8, from which connecting leads 10 and 11 extend to the exterior of the shell portion through an opening 12.

The sensitivity of the device may be greatly increased by providing means therein for the suppression of undesired eddy-currents in the material composing the magnetic circuit, namely, the central permanent magnet and the encircling rims 5 and 7. I have successfully accomplished the suppression of such eddy-currents by making a plurality of radial saw-cuts in all of these elements, or, if desirable, the pole piece may be provided with cuts and the elements 5 and 7 may be laminated.

The rim 7 has a central projecting flange 13 which is exteriorly threaded and carries a compression device 14 thereon.

A cup-shaped element 15 of non-magnetic material, such as aluminum or the like, extends into the gap between the central pole piece 2 and the annular elements 5 and 7 and is maintained centered therein by a washer 16 of resilient material, such as felt, which has a central protuberance 17 to fit into, and be carried by, a depression in the end of the central pole piece 2.

A circular washer 18 of resilient material is interposed between the bottom of the cup 15 and the pressure device 14, the pressure thereon being regulated by screwing the said device either in or out on the flange 13. The threaded edges of the pressure device are preferably provided with saw-cuts (not shown) in order that it may maintain whatever adjustment is given it.

The cup-shaped member 15 has a depression in the bottom thereof, through an opening in which extends a connecting device 19 which is held in position by a lock nut 20.

To otherwise free end of the connecting device 18 is attached to the upper end of a needle-carrying element 21. The element 21 is provided with trunnions 22 having reduced end portions. As shown in Fig. 5, the reduced end portions of the trunnions 22 fit

into openings 23 and 24 provided in the branches 25 and 26 of a resilient U-shaped bearing device 27 which is affixed to the rim 7 by means of a plurality of bolts or screws 28. The branches 25 and 26 are so arranged as to exert a slight amount of pressure axially upon the trunnions 22 in order to thereby compensate for wear caused by the oscillation of the needle-carrying element 21 therebetween.

The needle-carrying member 21 is provided with a needle-holding set screw 30 which so projects into it that a line drawn through the axis of the set screw would cut the axis of the supporting trunnions 22. By reason of this specific location of the set screw 30, pressure exerted thereon during the process of inserting or removing a needle will not be transmitted to the cup-shaped member 15 to any great extent.

The needle-carrying member 21 is preferably extremely rigid throughout that portion thereof which accommodates the needle and is provided with a semi-rigid, or relatively flexible portion, adjacent the point where it is affixed to the connecting device carried by the protuberance in the bottom of the cup-shaped element 15.

Referring to Figs. 3 and 4, the resilient adjusting bearing may be so modified that the openings in the branches 25 and 26 thereof are interiorly threaded and carry a plurality of hollow screw-threaded elements 31 and 32 having ends counter-sunk to accommodate the reduced ends of a trunnion 33. When a modification, such as is illustrated in Fig. 3, is employed, the device is so initially adjusted by turning in or out the screw-threaded bearing devices that a slight pressure is exerted axially upon the trunnions. As the trunnions and the bearing devices wear during use, this initial pressure is relieved without, however, permitting the device to work loose and rattle.

In the assembly of the device illustrated in Fig. 1, the shell element 4 is first mounted on the base 1 and screwed down as far as possible. The coil 8 is next placed upon the rim 5 of the shell and the second rim 7 is screwed in place, thus holding the coil firmly in position. The felt washer 16 is next mounted on the central pole piece 2 and the cup-shaped member 15 slipped over it and centered in the air gap. The resilient washer 18 is next placed around the protuberance of the cup-shaped member 15, and the pressure device 14 is placed on the flange 13 and turned down sufficiently to exert a slight amount of pressure on the cup-shaped member through the washer 18.

The resilient bearing 27 may then be mounted on the rim 7 by means of the screws 28 and, by expanding slightly the branches 25 and 26 thereof, the trunnions 22 of the

needle-carrying member 21 may be positioned in the bearing openings 23 and 24.

5 The connecting device 19 may then be soldered directly to the reduced extension of the needle-carrying member 21, and the device is then ready to be adjusted and tested.

10 In Fig. 1 of the drawings, a cup-shaped cover 34 is shown as being press-fitted upon the end of the device, this cover being made removable for the purpose of changing the pressure exerted upon the damping means.

15 The operation of my improved pick-up device may probably best be explained by considering it to be a combined generator and transformer, the cup-shaped member 15 serving as a component part of each.

20 When the cup-shaped element is caused to vibrate in the air gap, eddy-currents are induced therein, and, since the resistance of the circular portion is very low, these currents may reach a considerable magnitude.

25 The currents thus generated flow circumferentially of the cup-shaped element and, in so flowing, induce potentials in the secondary coil which is linked with the flux of these currents. The potentials thus induced in the secondary coil, and the frequency of the currents caused to flow thereby will correspond to the amplitude and frequency of the sound 30 record which is being utilized to actuate the needle-carrying element.

35 The dimensions shown in Fig. 1 are relatively correct, although the device, as a whole, is exaggerated in size. The needle-holding element in an actual embodiment is only a trifle longer than the usual phonograph needle and, consequently, has a very small mass. The device has but a very slight inertia and, accordingly, it is sensitive to the most delicate sinuosities of the record.

40 By reducing the length of the needle-carrying element to a minimum and by increasing its intrinsic rigidity, the possibility of the element itself vibrating is substantially eliminated. This specific construction of the needle-carrying arm I consider a very important part of the present invention, inasmuch as it largely prevents unpleasant buzzing and scratching noises which, in devices constructed according to the prior art, rendered the reproduction of music somewhat unpleasant.

45 I have described the damping means as being composed of felt. If this material is used, it is preferable to employ that grade known as "piano hammer felt," of the type employed on piano hammers at the treble end of the scale. Although serving primarily as a damping material, the felt has sufficient body to enable it to continue to function as 50 centering means over a long period of time without detrimental sagging. The damping of the motion is accomplished both by the internal friction of the particles of the felt and by the opposition to the passage of 55 trained air therethrough.

In lieu of the felt, I have found it feasible to employ several layers of silk or analogous material, such material being particularly useful for the washer 18 which lies between the cup-shaped element 15 and the pressure device 14. It is also feasible to employ a combination of silk fabric and felt in order to obtain the requisite degree of damping.

70 By adjusting the pressure of the pressure device 14 against the damping washer, more or less resistance may be interposed against the movement of the cup-shaped member 15. If the pressure device is so adjusted that the damping means is compressed, the pick-up 75 will respond mainly to high frequencies, whereas, if the damping means is but loosely held, the low frequencies will be accentuated.

80 The most marked advantage of a device built according to my invention lies in the 85 elimination of moving conductors. In electro-dynamic pick-up devices, such as that shown in the patent to Jones referred to above, it is necessary that the moving coil be supplied with flexible conductors in order 90 that the currents representing the sound being reproduced may be led therefrom to an amplifying device. Such flexible conductors are a constant source of trouble, inasmuch as they are continually subjected to bending forces and, consequently, very often break 95 in service. The cup-shaped single-turn primary of my device requires no external connections, and such connections are not required if the cup-shaped element is replaced 100 by a non-magnetic form carrying a plurality of turns which are short-circuited. The single-turn conductor is perhaps preferable 105 since, in that form, the resistance is much less than when a plurality of turns are used, and, consequently, a larger eddy-current will tend to flow in it.

110 Although I have shown and described only a single specific embodiment of my invention, I am thoroughly aware of the fact that many modifications may be apparent to those skilled in the art. My invention, therefore, is not to be limited except insofar as is necessitated by the prior art and by the spirit of the appended claims.

115 I claim as my invention:

1. In a pick-up device, the combination between a closed-circuit primary coil mounted for motion in a magnetic field, a secondary coil in operative relation thereto, means comprising an actuatable needle holder for moving said primary coil in said field, and adjustable damping means independent of said needle holder for controlling said movement.

120 2. In a pick-up device, a magnetic circuit comprising a central element of one polarity, a shell supporting said element and carrying a plurality of annular elements of opposite polarity, the said annular elements so 125 encircling said central element as to provide a 130

plurality of circular gaps therebetween, a secondary coil encircling said central element intermediate said annular elements, a closed-circuit primary coil of non-magnetic material movably mounted in said gap and stylus-receiving means connected with said primary coil.

3. In a pickup device, a magnetic circuit comprising a central core, a shell encircling said core, a plurality of annular elements extending inwardly from said shell to provide a plurality of air-gaps, a primary element movably supported in said gaps, a secondary winding positioned in the annular space defined by the said inwardly extending annular elements and the central core, whereby a secondary magnetic circuit having relatively low reluctance is established for flux arising from currents induced in said primary element and stylus-receiving means connected with said primary element.

4. In a pick-up device, a magnetic circuit having a gap therein, a closed-circuit primary element mounted for oscillatory motion in said gap, a secondary coil disposed in inductive relation to said primary element adjacent to said gap, a stylus-holding element affixed to said primary element for imparting motion thereto, and adjustable damping means for controlling the motion of said primary element, whereby, when said primary element is caused to move in said gap, electrical potentials are set up in said secondary coil by reason of currents induced in said primary element, and the frequency-response of said device may be controlled.

In testimony whereof, I have hereunto subscribed my name this 16th day of June, 1927.

JURJEN S. HIGH.
